C. HEINTZE

MEDICAL ELECTRICAL APPARATUS

Filed Jan. 28, 1926

Ernest Heintze
INVENTOR.

UNITED STATES PATENT OFFICE.

CONRAD HEINTZE, OF CHICAGO, ILLINOIS, ASSIGNOR TO HANOVIA CHEMICAL AND MFG. CO., A CORPORATION OF NEW JERSEY.

MEDICAL ELECTRICAL APPARATUS.

Application filed January 28, 1926. Serial No. 84,334.

This invention relates to medical electrical apparatus; particularly it relates to apparatus adapted to be used to expose human bodies for the purpose of treatment to electric rays emanating from the apparatus. It is well known to expose a human body to the ultra-violet rays of a quartz lamp of the Zickler type. In known devices used in connection with such lamp the lamp had to be moved by hand 5 in order to expose the whole body to be treated with the rays emanating from said lamp, and it was practically impossible to move the lamp in such a manner, that the whole body was affected equally and uniformly by the ultra-violet rays. In addition thereto it was necessary to regulate the speed with which the lamp was moved with respect to the distance of the lamp from the body to be treated, because the efficiency of the 10 quartz lamp depends on the distance of the lamp from the body exposed to the rays of the lamp. The ratio in which the efficiency changes is as the square of the difference in distance. It is well known that an overexposure of a body to the ultra-violet rays of a quartz lamp will result in bad injuries. If therefore the lamp is arranged very near to the body, it will be necessary to move the lamp with a much greater speed than 15 would be necessary, if the lamp would be further away.

The object of the invention is therefore to overcome the disadvantages inherent to the apparatus used heretofore to expose a human body to the ultra-violet rays of a quartz lamp and to accomplish this object the apparatus according to the invention comprises means to move the quartz lamp of the apparatus at a uniform ratio of speed. A further object of the invention is to regulate the 20 distance of the lamp from the body to be treated in such a manner, that the rays from the lamp will affect every portion of the body to a certain degree and a still further object of the invention is to adjust the speed of the movement of the lamp and the distance of the lamp from the body to be treated in relation to each other in such a manner, that the best results will be obtained with the smallest size lamp possible 25 and with the least possibility of danger to the patient.

Another object of the invention is to provide an apparatus the movement of the lamp whereof may be automatically reversed at

the end of the path of movement in one direction, so that the body of the patient may be exposed to the rays on one side during the travel of the lamp in one direction and on its other side during the movement of the lamp in the other direction. Another object of the invention is to provide an apparatus the driving power whereof is furnished by a reversible electric motor. A still further object of the invention is to provide means for automatically cutting out the motor without cutting out the lamp, when the latter has been returned to its starting position at the end of a treatment. It is well known, that a quartz lamp does not develop its full 30 power immediately upon being switched on, but that it takes some time for a quartz lamp to reach its full efficiency. It is therefore a saving of time to keep the quartz lamp burning and cut out the motor, when changing 35 patients. It is finally an object of the invention to provide means for protecting the patient against the influence of the rays of the lamp, when the latter is at a standstill, after the motor is cut out for the purpose of 40 changing patients.

With these and other objects not specifically mentioned in view the invention consists in certain parts and certain combinations of such parts more fully set forth in 45 the following specification and specifically mentioned in the appended claims.

In the drawings forming a part of the specification and wherein like parts are indicated by like reference characters

Fig. 1 is an elevation of an apparatus embodying the invention, the apparatus being indicated as suspended from the ceiling of a room.

Fig. 2 is an end view of Fig. 1.

Fig. 3 is a perspective view showing the frame of an apparatus according to the invention attached to a bench or a table adapted to support a body to be treated.

A quartz lamp 1 of well known construction is surrounded by a reflector 2 adapted to direct the light rays of the lamp downwardly upon a patient lying upon a bench or table 3 (see Fig. 3). To the top portion of the reflector trolley wheels 4 are attached in any convenient and suitable manner. Said wheels ride upon a member of a supporting frame 5. The frame consists of the trolley member 6, a rectangular sub-frame 7, and the vertical members 8 connecting the

100

105

110

sub-frame and the trolley member. The whole frame may be made of pipes connected together by means of standard fittings. On one of the vertical members 8 a bracket 9 is secured supporting an electric reversible motor. A friction disc 11 is mounted on the shaft 12 of the motor and frictionally engages a second friction disc 13. The second disc is slidably but not rotatably mounted on 10 a shaft 14 rotatably journaled in a casing 15 fastened to and carried by the adjacent vertical member 8 and the trolley member of the frame. The second disc 13 has a hub 16 surrounding the shaft 14 and extending outwardly from the disc. A set screw 17 extends through the hub and engages the shaft 14 to hold the second disc in any adjusted position in relation to the first disc 11. By loosening the set screw the second disc may 20 be moved radially to the first disc and thereby the ratio of speed transmitted by the first disc to the shaft 14 may be regulated. A worm 18 is mounted on the portion of shaft 14 located inside of the casing 15 or the 25 worm may be formed integrally with said shaft. Another shaft 19 extending at right angles to the shaft carrying the worm is arranged in the casing 15 and rotatably journaled therein. This shaft 19 carries a worm gear 20 meshing with the worm 18 and a pulley 21.

On the other end of the frame 5 the vertical member 8 and the trolley member 6 support a second casing 22. A shaft 23 extends through this casing and is rotatably journaled therein. The shaft extends parallel to and at the same level with the shaft 19 carrying the worm 20 and the pulley 21. Another pulley 24 is mounted on shaft 23 40 and a steel cable 25 or the like is trained over the two pulleys. To the ends of the cable spiral springs 26 and 27 respectively are fastened and the free ends of these springs are connected to the members 28 45 mounted on the reflector 2 and carrying the trolley wheels 4. Thus it will be apparent, that the reflector carrying the quartz lamp will be moved over the whole length of the frame 5, when the motor 10 is started, and 50 that the ratio of speed of this movement can be regulated by the adjustment of the second disk 13 in relation to the first disk 11. Eyes 29 are fastened to the casings 15 and 22, and chains 30 engaging these eyes 55 extend upward therefrom and may be fastened in any desired and suitable manner to the ceiling of the room wherein the apparatus is located, or the chains may be trained over suitable pulleys (not shown) and counter weights (not shown) may be used to 60 balance the frame and the lamp carried thereby in any desired distance from the patient to be treated.

A switch device 31 has the terminal posts 65 32 and 33. These posts are inserted in the

circuit (not shown) feeding the motor 10. Normally the spring contact 34 contacts with both terminal posts and thereby closes the circuit. On the inner end of the spring contact a hook shaped member 35 is mounted 70 having an inclined cam surface 36. When the motor rotates in such direction, that the lamp travels to the right in Fig. 1 the upper right hand end of the reflector will engage the cam surface 36 and will lift the 75 hook shaped member and the spring contact from the terminal post 32 thereby opening the motor circuit, so that the motor is cut out and the movement of the lamp is stopped. In order to start the motor again 80 while the spring contact is held in lifted position by the reflector a hand operable switch having the contacts 37 is provided. The contacts 37 are connected with the terminal posts 32 and 33 respectively, so that the motor circuit will be closed, when the contacts 37 are actuated by hand. Thus it will be seen, that at the end of its travel toward the right end in Fig. 1 the lamp will be 85 automatically stopped and will not start on its return movement until the hand operable contacts are actuated to close the circuit.

In the casing 15 shown on the left hand end of Fig. 1 a reverse switch is provided (not shown), which is actuated by means of lever 38 to reverse the motor. In Fig. 1 the lever is shown in full lines in such a position as to cause the motor to rotate in such a direction, that the lamp travels toward the left. The carrier member 28 at the left end 95 of the reflector has a pin or the like extending toward the left. When the lamp approaches the end of its movement toward the left, the pin 39 will engage the lever 38 and move it into the position shown in Fig. 1 in dotted lines thereby reversing the motor 10, so that the lamp movement is also reversed and the lamp travels now toward the right hand end of the apparatus. In the casing 22 located at the right hand 100 end of the frame a second lever 40 is pivotally mounted as at 41 and a steel cable or the like 42 connects the levers 38 and 40. When pin 39 moves lever 38 out of the position shown in full lines into 105 the one shown in dotted lines, the cable will pull the lever 40 out of the position shown in full lines into the position shown in dotted lines. The lever 40 has a pointed end engaging a spring 43 fastened 110 to a shoulder 44 in the casing 22 and tending to hold the lever 40 in the adjusted position. The carrier member 28 on the right hand 115 end of the reflector is also provided with a pin 45 or the like extending toward the right and adapted to engage the lever 40, when the lamp approaches the end of its movement toward the right. By this engagement the lever 40 will be returned into the position shown in full lines. At the same time will 120

also the lever 38 be returned to the position shown in full lines so that the motor is again reversed to move the lamp toward the left. At approximately the same time however,

5 that the motor is reversed the spring switch 35 is opened by engagement with the reflector 2 so that the motor is cut out, but is put in condition to move the lamp toward the left as soon as the hand switch 37 is closed.

10 It is usual to use plain incandescent lights in connection with quartz lamps and for this purpose carriers 46 are mounted on the longitudinal members of the subframe 7. Set screws 47 extend through the carriers 46 15 and engage the frame members so that the carriers and the reflectors 48 supported by said carriers and surrounding the plain incandescent lamps may be angularly adjusted in relation to the frame and in ratio to the 20 distance from the object to be exposed to the light rays.

On the right hand end of the frame, that is on the side where the movement of the lamp is interrupted, a shade 57 is fastened to 25 the frame in any suitable manner. The shade extends underneath the lamp and parallel to the frame. It protects the patient against the rays emanating from the lamp, while the same stands still.

30 In Fig. 3 it is diagrammatically shown how an apparatus according to the present invention may be fastened or mounted on a bench or table adapted to support a patient to be treated with said apparatus. A bench or the like 3 may be constructed in any suitable manner, for instance as shown with a frame made of pipes, and to the end members 49 of said frame standards or posts 50 may be fastened in any suitable manner for 35 instance by means of T's 51. The standards support adjustable brackets 52 carrying pulleys 53. A cable 54 is trained over these pulleys and is fastened with one of its ends to trolley member 6^a of the frame 5^a corresponding to the members 6 and the frame 5 described above. A cable 55 is trained 40 over one of the pulleys 53 and is fastened with one of its ends to the end of trolley member 6^a opposite to the end to which cable 54 is fastened. The two free ends of 45 the cables are connected to a counterweight 56, so that the frame 5^a will be always kept in a horizontal plane while it is being moved up or down to adjust the distance of the 50 lamps carried by frame 5^a from the patient.

Having described my invention what I claim as new and desire to secure by Letters Patent is:

60 1. In a device of the class described a quartz lamp, a frame slidably supporting the lamp, means for moving the lamp along the frame, means for reversing the movement of the lamp, and means carried by the

lamp for automatically actuating the reversing means upon arrival of the lamp at the 65 end of its path of movement in either direction.

2. In a device of the class described a quartz lamp, a frame slidably supporting the lamp, means for moving the lamp along 70 the frame, means for reversing the movement of the lamp, means carried by the lamp for automatically actuating the reversing means upon arrival of the lamp at the end of the path of its movement in either 75 direction, and means adapted to be actuated by the lamp upon arrival thereof at the end of its path of movement in one direction for stopping the movement of the lamp.

3. In a device of the class described a quartz lamp, a frame slidably supporting the lamp, means for moving the lamp along the frame, means for driving said moving means, means for reversing the movement of the driving means, means carried by the 80 lamp for automatically actuating the reversing means upon arrival of the lamp at the end of the path of its movement in either direction, and means adapted to be actuated by the lamp upon arrival thereof at the end 85 of its path of movement in one direction for stopping the movement of the driving means.

4. In a device of the class described a quartz lamp, a frame slidably supporting 95 the lamp, means for moving the lamp along the frame, means for driving said moving means, means for reversing the movement of the driving means, means carried by the lamp for automatically actuating the reversing means, upon arrival of the lamp at the end of the path of its movement in either direction, means adapted to be actuated by the lamp upon arrival thereof at the end 100 of the path of its movement in one direction for stopping the movement of the driving means, and hand operable means for starting the driving means, while the stopping means 105 are operated by the lamp.

5. In a device of the class described a 110 quartz lamp, a frame slidably supporting the lamp, means for moving the lamp along the frame, means for reversing the direction of the movement of the lamp upon arrival of the lamp at the end of the path of its 115 movement in either direction, means for stopping the movement of the lamp upon arrival of the lamp at the end of the path of its movement in one direction, and means for preventing the rays of the lamp from 120 striking the patient while the movement of the lamp is interrupted.

In witness whereof I have affixed hereunto my signature.

CONRAD HEINTZE.
